UNITED STATES PATENT OFFICE.

JOHN H. VAILE, OF DAYTON, OHIO.

APPARATUS FOR ACTUATING HYDROSTATIC PRESSES.

SPECIFICATION forming part of Letters Patent No. 424,040, dated March 25, 1890.

Application filed July 24, 1889. Serial No. 318,521. (No model.)

To all whom it may concern:

Be it known that I, JOHN H. VAILE, a citizen of the United States, residing at Dayton, in the county of Montgomery and State of Ohio, have invented certain new and useful Improvements in Apparatus for Actuating Hydrostatic Presses, of which the following is a full, clear, and exact description, reference being had to the accompanying drawings, forming part of this specification.

My invention relates to all classes of presses wherein a liquid is used to exert the pressure; and, as coming primarily within the object of my invention, it relates to hydrostatic presses for compressing substances of a very soft or plastic nature—such as lard, paraffine, and the like—and more particularly for expressing oil from meal, seeds, or other oleaginous substances.

It has for its object the improved construction of the apparatus by which the operation is rendered certain and as nearly perfect as possible.

The novelty of my invention will be herein set forth, and specifically pointed out in the claims.

In the accompanying drawings, Figure 1, Sheet 1, is an elevation, partly in section, of so much of the apparatus as is necessary to illustrate my invention. Fig. 2, Sheet 1, is a modified form of the variable accumulator embodied in the apparatus shown in Fig. 1. Fig. 3, Sheet 2, is an enlarged sectional elevation of the automatic valve mechanism embodied in the construction shown in Fig. 1. Fig. 4, Sheet 3, is a plan view of the valve mechanism of Fig. 3. Fig. 5, Sheet 3, is a sectional elevation through the dotted line α α of Fig. 4, looking in the direction of the arrow. Fig. 6, Sheet 4, is an enlarged sectional elevation through the dotted line y y of Fig. 4, and looking in the direction of the arrow. Fig. 7, Sheet 5, is an enlarged sectional elevation of one of the hand-controlling valves embodied in the construction shown in Fig. 1. Fig. 8, Sheet 6, is a plan view showing the connection of the apparatus with a set of four presses.

The same letters of reference are used to indicate identical parts in all the figures.

Referring to Fig. 1, A and B are two pumps—in this instance steam-pumps—of the usual

or any suitable construction, pumping from a supply-tank C, containing the liquid—usually oil—for actuating the presses. D is the cylinder of a hydrostatic press of the usual or any suitable construction, and E its piston, to which the press-platen (not here shown) is secured. F is a strong air-tight vessel, which I designate a "variable accumulator," and into which the pump B pumps through a pipe G, provided with a check or other valve a .

Interposed and properly supported between the variable accumulator and the press is the valve mechanism illustrated in Figs. 3, 4, 5, 6, and 7, where H is the valve-casing, having an inlet-passage b, into which a pipe c from the variable accumulator enters. From the passage b there is a vertical passage d, having seated therein a check-valve e. The passage d opens into a horizontal passage f, having an outlet, from which a pipe c' extends on its way to the press. A pipe I extends from the pump A and enters a passage g in the casing H, which passage communicates by a port h 75 with the passage f, said port being provided with a vertical valve J, packed through a plug K in the top of the casing and projecting above the same. L is a similarly-placed plunger, whose lower end rests upon or may 80 be connected to the check-valve e. Between lugs i on the top of the casing is pivoted a lever-arm M, which constantly bears upon the valve J on one side of its pivotal point, and is directly over the plunger L on the opposite 85 side. The projecting end of the lever M on the side of the valve J is provided with an adjustable weight N for holding the valve J down to its seat, except as hereinafter explained. Between the weight and valve J 90 there is a third plunger O, directly under the lever L, and held up in contact therewith by a spring j in the bottom of the core k, containing said plunger. A small passage l, Fig. 6, extends laterally from the bottom of the 95 bore k, and communicates with a second bore m, containing a vertical plunger P, whose lower end serves as a valve to close the passage l, except as hereinafter explained. A second weighted lever Q, Figs. 4, 5, and 6, pivoted to lugs n on the casing H, serves to hold down the plunger P. A vertical passage o 100 extends from the bottom of the bore m, and communicates by a transverse passage p with

a longitudinal passage q , extending to and communicating with a vertical passage q' , entering the passage f between the check-valve e and plunger J . The bore k has a small outlet-passage r , from which a return-pipe s extends back to the tank C , and is provided with a valve or stop-cock t near the casing H . The pipe c' , leaving the casing H , extends to and enters the hand-valve casing R , Fig. 7, at u . This casing has two screw-valves S and T , the former for admitting the liquid to the press through the passages v , w , and z , and pipe c'' , extending from the latter passage, and the latter for permitting the liquid to escape from the press after the pressing operation has been completed through the return-pipe U to the tank C . Interposed between the passages v and w is a check-valve a' , which is closed by the back-pressure when the valve T is opened.

A' B' , Fig. 1, are the steam-supply pipes for the pumps, and they are provided with reducing-valves C' of any suitable construction.

In Fig. 8 I have shown the manner of connecting a series of presses D' with the mechanisms above described, and I would thus describe the operation of the apparatus.

The pump A is a high-pressure pump, adjusted, for illustration of the operation of the apparatus, to a constant duty, say, of four thousand pounds, while the pump B is a low-pressure pump, adjusted, for illustration of the operation, to a duty, for instance, that cannot exceed seven hundred pounds. The weight N is adjusted to overcome a pressure of four thousand pounds exerted on the under side of the valve J , combined with a pressure of slightly less than seven hundred pounds, while the weight on the lever Q is adjusted to overcome just seven hundred pounds exerted on the under side of the plunger P . The accumulator is about two-thirds filled with oil, and the tank C is also supplied with oil.

Supposing that the material in the press is oil-meal, cotton, or linseed applied in layers in the usual way, and the operation of expressing the oil is ready to be begun for the first time, steam is admitted to both pumps.

The pipe I of the pump A being closed by its valve J at a pressure of the weight N , which cannot be overcome by the pressure from the pump A acting on the under side of the valve J alone, said pump remains stationary, while the pump B begins pumping from the tank C into the accumulator F , gradually filling said accumulator and compressing the air therein until an indicator E' shows the internal pressure to be seven hundred pounds.

This point being reached, the pump B stops, because, as before explained, it is so adjusted that it cannot overcome a greater resistance. The attendant now opens the valve S of the press to be operated, the valves T being all closed, and also opens a valve F' , Fig. 8, in the pipe c . The oil at once rushes through the pipe c and passages b d , lifts the check-

valve e , and passes on through the passage f and pipe c' into the casing R , where it lifts the check-valve a' and continues on through the passages w z and pipe c'' to the press, and raises the platen rapidly, but with a constantly-decreasing pressure, so that by the time working contact is made the pressure is only just sufficient to express the free and easily-expressed oil without bursting the bags and squeezing out the meal. As the pressure in the accumulator decreases by the escape of the oil to the press, the pump B begins to work again and gradually restores the pressure until the meal in the press having become condensed, and the pressure in the accumulator having been restored to seven hundred pounds, the oil through the passages q' , q , p , and o instantly counterbalances the weight of the lever Q , and, raising the plunger-valve P , passes on under the plunger O , and acting with the pressure on the valve J raises said plunger and valve simultaneously and overcomes the weight N . This at once admits the high pressure from the pump A , which continues to act on the press until the pressing operation is completed. As soon as the high pressure is admitted the check-valve e is instantly closed both by the back-pressure and by the action of the lever M on the plunger L , as will be readily understood, and the pump B continues to work, as before described, until a pressure of seven hundred pounds is re-established in the accumulator, when it again stops, though the pump A continues its work. When the pressing has been completed, the attendant closes the valves S and F' and opens the valve T , whereupon the oil in the press escapes through the pipe U to the tank C , and the press is thus let down. The attendant next opens the cock t , to permit the escape of the oil through the pipes from under the plunger O , which is then forced down by the weight N and the valve J is thereby reseated. The cock t is at once closed and the operation is ready to be repeated.

In Fig. 8 all of the casings R , of which there is one for each press D' , are connected in front of the valve-seat of the valve S by pipes b' , so that any press of the series may be acted on as above described.

The substitute form of variable accumulator shown in Fig. 2 is merely a packed piston in a cylinder connected to both the valve-casing H and pump B , and the piston is loaded with a series of pick-up weights, as described in my patents of November 26, 1889, Nos. 415,750 and 416,020.

Having thus fully described my invention, I claim—

1. The combination, with a hydrostatic press having a source of high-pressure supply and a variable accumulator having a source of low-pressure supply, of interposed valve mechanism consisting of a casing connected with the variable accumulator and source of high-pressure supply, with a check-

valve interposed between said connections, a plunger-valve for the high-pressure inlet held by a constant weight, and two independent plungers acted on by the maximum pressure from the variable accumulator to overcome said constant weight and release the plunger-valve for the admission of the high pressure, substantially as described.

2. In hydrostatic press apparatus, the valve-casing H, provided with the inlets b and g, outlet c', and passages d, f, q', q, p, o, and l, a check-valve e, seated in the passage d, the plunger-valve J and plungers O P, and the weighted levers M Q, for the plungers P O and valve J, substantially in the manner and for the purpose described.

3. In a valve-casing H, substantially as described, the arrangement of the check-valve e with its plunger L, the valve J and plunger O, and the superimposed weighted lever M, pivoted at a point between the valve J and plunger L, as and for the purpose specified.

4. The combination, with a high-pressure pump, of a low pressure and its accumulator, a valve-case, and passages connecting it with the accumulator and with the press, two dif-

ferently-weighted valve devices normally held closed by independent weights, and passages connecting, respectively, the passage from the accumulator with the lighter-weighted 30 valve device, the said valve device when opened with the heavier-weighted valve device, the high-pressure pump with the latter valve, and the said valve with the passage to the press, substantially as described. 35

5. The combination, with the high and low pressure pumps, the accumulator, and the press, of the valve-casing R, having the passages z, w, and v, the hand-valves S and T, and the check-valve a', interposed between 40 the said passages w and v, and arranged to close the latter passage by back-pressure when the said valve T is opened, a valve mechanism interposed between the said valve-casing R and the said accumulator and pumps, 45 and suitable pipes or passages connecting said pumps, accumulator, valve mechanism, valve-casing R, and press.

JOHN H. VAILE.
